DESIGN FOR A COMBINED ASH TRAY AND HOLDER FOR SMOKERS' ARTICLES

John G. Vasquez, Hartford, Conn.

Application April 25, 1945, Serial No. 119,213

Term of patent 14 years

(Cl. D85—2)

To all whom it may concern:

Be it known that I, John G. Vasquez, a citizen of the United States, residing at Hartford, in the County of Hartford and State of Connecticut, have invented a new, original, and ornamental Design for a Combined Ash Tray and Holder for Smokers' Articles, of which the following is a specification, reference being had to the accompanying drawing, forming a part thereof.

In the drawing:

Fig. 2 is a side elevation, and

Fig. 3 is an elevation taken from the right hand end of Fig. 1.

I claim:

The ornamental design for a combined ash tray and holder for smokers' articles, as shown.

JOHN G. VASQUEZ.
